SLEEVE CONSTRUCTION

Max C. Schrank, Bridgeton, N. J.

Application March 20, 1942, Serial No. 435,487

3 Claims. (Cl. 2-125)

This application relates to garments and more particularly to the sleeve construction thereof.

An object of this invention is to provide a sleeve construction suitable for garments of the sport or work type, in which the greatest possible freedom of the arm and shoulder is provided.

A further object is to provide a construction which will include the benefits mentioned but which will be neat in appearance and do away with the customary folds and tucks now used for that purpose.

Other objects and purposes of the invention will become apparent as the description proceeds.

In the accompanying drawings—

Fig. 1 is a front view of a garment embodying my sleeve construction;

Fig. 2 is a rear view of the same garment;

Fig. 3 is a cross-sectional view of the sleeve construction taken on the line 3-3 of Fig. 1;

Fig. 4 is a view of the pattern or blank from which the sleeve is made;

Fig. 5 is a view of the pattern for the front of the garment;

Fig. 6 is a view of the pattern for the rear of the garment.

The garment 10 may be of any desired type having front panels 11 and a rear panel 12. The panels 11 and 12 have shoulder portions 13 and 14 which are adapted to be joined together by the seam 15 to form the shoulder.

The sleeve blank 16 is cut with a straight edge 17 which forms a cuff portion, and a straight edge 18 at right angles thereto. The opposite edge 19 of the sleeve blank is curved and this forms the inner shoulder portion which is joined to the edges 20 and 21 of the front and rear blanks. The lower portion of the sleeve blank is cut away at 22 to form a tab 23 having a lower straight edge 24.

In assembling the garment illustrated in the drawings the blank 12 is joined to the blank 11. As has been pointed out the shoulder portions 13 and 14 are joined by the seam 15. It will be noted that the blank 12 is considerably longer than the blank 11 so that the portion 14 may extend over the front of the shoulder. The blank 16 is then folded so that the points 31 and 32 are brought together and the edges 18 and 22 are sewn together by the stitches 25. This brings the point 33 into approximate alignment with the point 34 and causes the tab 23 to be folded under at the rear of the armpit. The edge 19 is then stitched to the edges 20 and 21 to form the shoulder. As will be noted from 55

Figures 5 and 6 when the panels 11 and 12 are brought into an even position the panel 11 is considerably shorter and the point 35 will register on the edge 26 considerably below the point 36. When the sleeve is fastened to the garment the edge 24 contacts the back portion 12 along the edge 26 with the point 37 meeting the edge 26 where the point 35 of the panel 11 contacts the edge 26 and with the point 33 contacting the edge 26 at about the point 36. This produces a sleeve in which the tab 23 is at the rear of the armpit and thus provides additional material for greater freedom at that point.

It will be appreciated that, while I have shown my construction with a short sleeve, the length of the sleeve has no effect upon my invention and that the same construction may be used with a longer sleeve. It will also be appreciated that with this construction greater freedom of movement is provided since there is no binding under the arm pit and the arms may be raised to a horizontal position without pulling on the body of the garment.

I claim:

25. 1. In combination with a garment having front and back portions defining an armhole, the armhole curve of the back portion being shorter than that of the front portion, with the upper part of the side edge of the back portion forming the remaining part of the armhole edge; a sleeve formed of a single blank, said blank having a wrist end, a convexly curved shoulder end, a straight side and an extended side, said last named side comprising a substantially rectangular lateral extension, to provide material in addition to a normal symmetrical sleeve blank, said extension having a concavely curved end edge adjacent the wrist end, an opposite end forming a continuation of the shoulder end, and a straight intermediate side connecting the ends of the extension; the said curved edge being secured to the said straight side forming a tubular sleeve, the intermediate side being secured to the upper part of the side edge of the back portion, the remaining end of the extension and the shoulder end of the sleeve being secured to the armhole curves of the front and back portions.

2. A garment sleeve formed from a single blank, said blank having a wrist end, a convexly curved shoulder end, a straight side and an opposed extended side, said extended side comprising a substantially rectangular portion connected to the blank and providing material in addition to a normal symmetrical sleeve blank, the said extended portion having a concavely curved edge

adjacent the wrist end and an opposite substantially straight edge, the curved edge and straight edge of the extended side being connected by a straight side edge; the said curved edge being secured to the straight side and forming a tubular sleeve, the shoulder end of which is adapted for attachment to a garment at armholes therein.

3. A garment sleeve blank comprising a wrist end, a convexly curved shoulder end, a straight side and an opposed extended side, said last named side comprising a substantially rectangular lateral extension, to provide material in addition to a normal symmetrical sleeve blank, the extension having a concavely curved end edge

5 adjacent the wrist end, an opposite end forming a continuation of the shoulder end, the curved end edge and said opposite end being connected by a straight side, whereby a tubular sleeve which may be secured to armhole curves in the front and back portions of a garment is provided when the said curved edge is secured to the straight side, the remaining side secured to the upper part of the side edge of the back portion of the garment and the remaining end of the extension and the shoulder end are secured to said armhole curves.

MAX C. SCHRANK.
